UNITED STATES PATENT OFFICE.

BERNARD L. GLAVIN, OF LOS ANGELES, CALIFORNIA.

CURTAIN HANGER.

Application filed December 14, 1921. Serial No. 522,365.

To all whom it may concern:

Be it known that I, BERNARD L. GLAVIN, a citizen of the United States, residing at Los Angeles, in the county of Los Angeles and State of California, have invented new and useful Improvements in Curtain Hangers, of which the following is a specification.

My invention relates to curtain hangers and the like, and the purpose of my invention is the provision of a hanger of extremely simple, durable and efficient construction which includes a track and roller supported brackets movable in the track and adapted to movably sustain curtains thereon, the construction of the track, rollers and brackets being such as to prevent twisting of the brackets and rollers thereby insuring of the proper movement of the rollers within the track.

I will describe one form of curtain hanger embodying my invention, and will then point out the novel features thereof in a claim.

In the accompanying drawings,

Figure 1 is a view showing in side elevation one form of curtain hanger embodying my invention in applied position.

Fig. 2 is an enlarged fragmentary view, partly broken away, and showing in side elevation the hanger shown in Fig. 1.

Fig. 3 is a fragmentary plan view, partly broken away, showing the hanger.

Fig. 4 is a view showing the hanger in end elevation.

Referring specifically to the drawings in which similar reference characters refer to similar parts, my invention, in its present embodiment, comprises a track designated generally at T and formed from a single length of metal bent longitudinally to provide an upper securing portion 15, depending parallel portions 16, and inwardly projecting track portions 17 which, as clearly shown in Fig. 4, are bent upon themselves for the purpose of reinforcement.

The track T is adapted to be secured to a suitable support such as the frame F of a passageway by means of screws 18 or other suitable fastening members which are extended through the upper portion 15 of the track, it being particularly noted that the application of the screws is facilitated by virtue of the spacing of the track portions 17.

Rollers R are mounted on the ends of a stub shaft 19 sustained in the parallel por-

tions 20 of a bracket designated generally at B, the latter also including a horizontal portion 21 connecting the parallel portions 20 and provided with an opening for the reception of the upper end of a hook 22. This end of the hook is rotatably but irremovably secured within the bracket by means of a head 23 fixed to the swaged end as clearly shown in Figs. 2 and 4.

In the applied position of the rollers within the track T, they are disposed for rolling contact upon the upper side of the track portions 17, it being particularly noted that the rollers are relatively wide to secure the greatest amount of traction possible. In this position of the rollers, the hook 22 is sustained in depending relation to the track by means of the bracket B, the latter also serving to maintain the rollers in proper position within the track. It is to be particularly noted as shown in Fig. 4, that the length of the bracket B is such that the parallel portions 20 project beneath the track portions 17 so that with their flat sides contacting with the confronting edges of the track portions, it will be clear that any twisting movement of the bracket is prevented. As a consequence of this arrangement, the rollers are maintained in the same rolling contact with the track portions at all times thus insuring of the free and unrestricted longitudinal movement of the bracket within the track.

In practice, the track T is adapted to sustain a plurality of brackets and hooks in effecting the supporting of one or more curtains in upright position as shown in Fig. 1, and by virtue of the unrestricted movement of the brackets and hooks within the track, it will be manifest that an easy adjustment of the curtains upon the hanger can be readily effected and without the possibility of the rollers jamming to prevent movement of the brackets.

Although I have herein shown and described only one form of bracket embodying my invention, it is to be understood that various changes and modifications may be made herein without departing from the spirit of the invention and the spirit and scope of the appended claim.

I claim as my invention:

A curtain hanger comprising a metal track including an upper sustaining portion, spaced depending portions, and inwardly bent track portions disposed in spaced relation to

each other, a bracket of U-shaped formation having the parallel portions thereof extended between the track portions, a stub shaft mounted in the parallel portions of the bracket at a point within the track, 5 rollers carried by the ends of the stub shaft and having rolling contact with the inner sides of said track portions, and a hook swivelly sustained on the horizontal portion of the bracket. In testimony whereof I have signed my name to this specification. 10

BERNARD L. GLAVIN.
